RECESSED SHOWER TUB

William A. King, Baltimore, Md., assignor of one-half to
Royden H. Wood, Jr., Clarksville, Md.

Filed Dec. 7, 1962, Ser. No. 72,761

Term of patent 14 years

(Cl. D4—4)

FIG. 1

FIG. 2

FIG. 3

FIG. 4

FIG. 5

FIG. 6

FIG. 7

FIGURE 1 is a perspective view of a recessed shower tub illustrating my design;

FIGURE 2 is a reduced top plane view;

FIGURE 3 is a bottom plan view;

FIGURE 4 is a side elevational view;

FIGURE 5 is an end elevational view;

FIGURE 6 is an elevational view of the opposite end; and

FIGURE 7 is a perspective view of a modified form of the recessed shower tub shown in FIGURE 1.

The portions shown in broken lines in FIGURE 7 are included for illustrative purposes only.

I claim:

The ornamental design for a recessed shower tub, as shown and described.
